TARGET TRAP

Arthur E. Roth, Prairie du Chien, Wis.

Application July 15, 1932, Serial No. 622,657

4 Claims. (Cl. 124—3)

The present invention relates to a target trap.

In throwing clay targets or pigeons, as they are generally called, either for trap, or skeet shooting, it is at present customary to grip the pigeon, which is a saucer-shaped disk of frangible material, between a pair of releasable fingers pivotally mounted on a throwing arm, which is swung outwardly by means of a spring, the fingers operating to release the pigeon and impart a spinning motion thereto.

An object of the present invention is to make an improved trap for the throwing of clay pigeons.

In order to attain this object, there is provided, in accordance with one feature of the invention, 15 a base having a table member pivotally and tiltably mounted thereon. A throwing arm is pivotally mounted above this table member to swing in a plane parallel to the upper surface of said table, and a spring member and a brake member 20 are mounted beneath the table to actuate the throwing arm and to prevent oscillation thereof upon completion of a throwing operation. Electrically energized trigger means are mounted to hold the throwing arm in a set position and to release it when it is desired to operate the trap, 25 said trigger means being manually operable, if desired.

These and other features of the invention will be more fully brought out in the following description and the accompanying drawings, wherein:

Figure 1 is a view in perspective of the under surface of the pigeon throwing portion of a trap embodying the present invention.

Figure 2 is a sectional view on the line 2—2 of Figure 1.

Figure 3 is a view in perspective of a brake actuating arm.

Figure 4 is a longitudinal, sectional view through 40 a spring supporting bracket, showing the spring and associated parts mounted thereon.

Figure 5 is a view in perspective of the complete trap, set up and ready to operate.

Figure 6 is a view, also in perspective, showing 45 the trap tilted up to throw a pigeon substantially vertically, showing the extremely wide limit of operation of which this trap is capable.

Figure 7 is a view, in elevation, showing the 50 under side of the throwing arm.

Figure 8 is a sectional view through the upper portion of the trap supporting base, showing a novel method of securing the legs in place.

Figure 9 is an enlarged view in elevation showing 55 a trigger member, the solid lines showing it

in released position, and the dotted lines showing it in set position.

Figure 10 is an enlarged, fragmentary view, showing an edge of the table at a point where the trigger mechanism is mounted, the throwing arm 5 being shown as engaged by the trigger, and a pigeon in position ready for throwing.

Figure 11 is an enlarged fragmentary view of the throwing arm, and a pigeon, showing how the serrated edge of the throwing arm engages the 10 pigeon on its intermediate step portion, which greatly reduces the likelihood of breakage of pigeons.

Figure 12 is a sectional view on the line 12—12 of Figure 2; and

Figure 13 is a view in perspective of a pigeon 15 guide and positioning member.

Referring to the drawings in detail, a trap supporting base A has three legs 1, which are preferably of iron pipe. These legs support a top member 2, which is preferably of hard wood, such as maple, having indentations 3 (see Figure 8) to receive the upper ends of the legs at an acute angle, as indicated in Figure 8. A triangular framework for retaining the legs 20 comprises strap iron members 4 secured to the under surface of the top member 2 and extending angularly outward and downward, the lower ends of these members being bent to substantially cylindrical form, as at 5, to receive a bolt 6 therein. 30 Three similar strap iron members 7 are connected to the strap iron members 4 by the bolts 6, which pass through the lower ends of the strap iron members 4. A disk 8, having an angularly disposed peripheral portion 9 is mounted to slide 35 freely on a bolt 10. A threaded handle member 11 is threaded onto the bolt 10 which passes through the center of the top member 2, so that by screwing the handle member 11 upwardly to raise the disk 8 into gripping engagement with the legs 1, the legs are forced outwardly against the triangular strap iron framework, and also into the recess 3 to firmly hold the legs in position. By unscrewing the handle member 11 to release the disk 8 from gripping engagement with the 40 legs, the legs may be readily removed when it is desired to transport the trap from one location to another.

A tiltable table and throwing arm assembly B comprises a bracket 12 resting upon the upper 50 surface of the top member 2 and pivotally secured thereto by means of a bolt 13 which passes through the horizontal portion of the bracket member 12. An adjusting handle 14 is connected to the support bracket 12 to extend rearwardly 55

therefrom and is provided with a hand grip portion 15 so that by means of this hand grip portion the trap may be moved pivotally from one side to the other to vary the trajectory of the pigeons 5 thrown by the trap. Pivotally mounted upon the vertical side portion of the bracket 12 is a second bracket member 16 which has the transverse upper portion 17 thereof (see Figures 1 and 2) fixedly secured to a table member 18, as by means 10 of bolts 19. The upper bracket member 16 is connected to the lower bracket member 12, as by means of a bolt 20, having a handle member 21 secured thereto by means of the bolt 20, which may be tightened to hold the brackets 12 and 16 15 in adjusted, tilted position. Fixedly secured to the upper bracket member 16 and to the table 18, as by means of bolts 22 (see Figure 1), is a spring supporting arm 23 which extends forwardly from the table member 18 and is bent downwardly at 20 its outer end, as at 24. This downwardly bent end portion is provided with an interiorly threaded stud 25 on which is secured a spring-adjusting screw 26 having an operating handle 27 fixedly secured to its outer end. The inner end of the 25 spring-adjusting screw is riveted as at 28 (see Figure 4) to form a head portion and is mounted to rotate freely in a spring end member 29 which is bent into gripping engagement with a heavy coil spring 30. The opposite end of the coil spring 30 from that to which is secured the member 29 is tapered inwardly as at 31 and within this tapered end is placed a smaller coil spring 32 of lighter tension than the spring 30. Inserted in the small end of the spring 30 and passing through 35 the small spring 32 is a rod 33 having a nut 34 and locknut 35 on the inner end thereof; these nuts being adapted to rest upon the smaller spring 32 to prevent withdrawal of the rod 33. The outer end of the rod 33 is hook-shaped as at 40 36 and is adapted to engage a bolt 37 (see Figure 1) secured to a brake drum 38. This brake drum 38 is preferably perforated for lightness, as at 39. The brake drum is fixedly mounted upon a pivot pin 40 which preferably has a 45 squared shoulder 41 to fit into a squared opening in the center of the drum 38 to fixedly secure the drum on the pivot pin. A nut 42 holds the drum 38 securely against a shoulder 43 on the pivot pin. The pivot pin is pivotally mounted in a bushing 50 44 which is mounted within an opening in the bracket 16 and in the table 18, and is securely held in position therein by means of a nut 45, a recess for which is preferably provided in the upper surface of the table 18. In Figure 2 the 55 device is shown in inverted position so that the recess for the nut 45 is in normally what is the upper surface of the table 18.

A brake operating arm 46 (see particularly Figure 1, 2 and 3), is composed of a strip of sheet metal having one end 48 thereof bent to cylindrical shape, as shown in Figure 3, and having an arm 49 of reduced width extending outwardly therefrom, this arm being provided with an opening 50 in its outer end. A metal brake supporting band 51, of spring metal, is formed substantially, circular in shape, of smaller external diameter than the internal diameter of the drum 38, and a strip 52 of brake band material is riveted to the outer surface thereof in the same manner 60 as a brake lining is applied to an automobile brake band. One end of the metal band 51 is mounted upon a post 53 threaded into an opening in the bracket 16. The other end of the brake band is curved inwardly, as at 54 and is adapted 65 to rest against the arm 46, as shown in Figure 12.

A spring wire ring 55 is provided around the bushing 44 above the brake operating arm 46, as shown in Figure 2, to hold the brake operating arm in position on the bushing.

A combined brake operating and trigger resetting arm 56 is pivotally mounted on a pin 57, threaded into an opening adapted to receive it in the bracket 16, and a cam 58, see Figure 1, for operating this arm is provided on the drum 38.

Figure 1 shows the cam 58 in engagement with the brake actuating and trigger resetting arm 56 to operate said arm. A rod 59 is inserted through an opening in the outer end of the brake operating and trigger resetting arm and also passes through an opening in an arm 60, which is adapted to actuate trigger 61. A coil spring 62 encircles the rod 59 beyond the arm 56 and the tension upon this spring is controlled by a nut 63 which is threadedly mounted on the rod 59. A rod 64 is mounted through an opening in the central portion of the arm 56 and passes through the opening 59 in the brake operating arm 46. A similar spring 65 and nut 66 are mounted upon the rod 64 beyond the arm 56.

A wire 67 is hooked into the trigger operating arm 60 on the opposite side of the pivot from the rod 59 and is connected to a coil spring 68, the opposite end of which is hooked into engagement with the bracket 16. The spring normally tends to move the trigger operating arm 60 to the trigger operating position shown in dotted lines in Figure 1. Outward movement of the arm 56 by means of the cam 58 causes the trigger operating arm 60 to be moved by the rod 59 to the set, or solid line position shown in Figure 1, 30 against the tension of the spring 68.

A member 69 (see Figure 1) is fixedly secured to the outer, or free, end of the trigger operating arm 60 to form an offset shoulder thereon, and this shoulder is adapted to be engaged by a metal plate 70 which is mounted on a bracket 71 by means of screws 72. These screws are each surrounded by small coil springs which normally hold the plate 70 outwardly so as to engage the shoulder formed by the member 69. An ordinary 45 electromagnet 73 is mounted in a housing 74 and the core of this magnet, when energized, draws the metal plate 70 toward it, releasing it from engagement with the shoulder formed by the member 69 and permits the coil spring 68 to 50 swing the trigger operating arm to the dotted line position shown in Figure 1, when the cam 58 is moved to clear the arm 56.

The trigger 61 is best shown in Figures 9 and 10 and comprises a strip of sheet metal pivotally 55 mounted upon a bolt 75 and having a pin 76 fixedly secured to said trigger adjacent the opposite end thereof to extend through a slotted opening 77 in the table 18. An upturned portion 78 is provided on the outer, or right-hand 60 end of the trigger, and is adapted to engage a stud 79 which extends downwardly from the lower surface of a throwing arm C. When the trigger is in the dotted line position shown in Figure 9, the upturned end portion 78 is in line with the 65 stud 79 when the throwing arm C is moved to a set position. When the trigger operating arm 60 is released to the dotted line position shown in Figure 1, this arm strikes the pin 77, where it extends below the table 18, knocking the trigger 70 outwardly out of engagement with the stud 79, thus allowing the throwing arm C to swing around under the impulse of the spring 30 and throw the targets in the manner indicated by the arrows shown in Figure 6. The throwing arm C, pref- 75

erably comprises two strips of sheet metal 80 and 81, the lower of which is preferably formed in the outline shown in Figure 7. Between the sheet metal arms 80 and 81 is provided a wooden member 82, and a second wooden member 83 is fitted on top of the upper sheet metal member 81 to round off the handle and prevent any sharp edges from injuring the hand of an operator. The intermediate wooden portion 82 is preferably formed to extend outward over a serrated edge 84 provided on the lower sheet metal member 80, which serrated edge engages the pigeon as it is thrown outwardly to thereby impart a spinning motion to the pigeon, which improves its flight through the air. The sheet metal members 80 and 81 are secured to the pivot post 40, as by means of spacing washers 85 and 86 and a nut 87, which firmly grip the arms between the washers and the nut and fixedly secures these arms to the pivot post 40.

A pigeon support member 88 comprises a curved guide strip of metal having pins 89 (see Figure 13) extending downwardly therefrom, adapted to enter openings 90 in the table 18. This curved guide member is adapted to be mounted upon the table 18, in either of two positions, as indicated in Figure 6. In this figure the pigeon guide member 88 is indicated in solid lines in the position it occupies when it is desired to throw singles, or but one pigeon at a time, the dotted lines indicating the position this guide member is mounted in when it is desired to throw doubles, or two pigeons at a time. In this Figure 6 a pair of pigeons to be thrown simultaneously are indicated in dotted lines, as are also the approximate paths of flight of the two pigeons indicated. The pigeon farthest out will leave the arm first, taking the course indicated by the lower line of dotted arrows, while the other pigeon, being in engagement with the arm longer will take approximately the line indicated by the upper line of dotted arrows. A single pigeon mounted on the guide member indicated in solid lines in this figure would take a course somewhere between these two lines of arrows.

The operation of the device is as follows, attention being directed particularly to Figures 1, 5 and 6, in the following description of the operation:

The throwing arm C is grasped manually by the operator, as shown in Figure 5, and is drawn down to the set position shown in Figure 6. A small coil spring 92 (see Figure 10), is mounted around a small bolt 93 and engages the pin 75 and lower end of the bolt 77, normally holding the trigger 61 in the solid line position shown in Figure 1. After the device is set, as shown in Figure 6, the arm C will be slightly past dead center, so that the coil spring 30 will tend to draw the arm around in the clockwise position from the set position shown in Figure 6. By turning the handle 27 the tension on the coil spring 30 may be adjusted, the stronger the tension on the spring, of course, the more powerful the throwing force of the arm C will be.

Assuming that it is desired to throw one pigeon at a time, the guide member 88 will be mounted in the solid line position shown in Figure 6, and one pigeon placed forwardly of the arm in the position occupied by the right hand pigeon 94. If it is so desired at the same time, a second pigeon 95 may be placed rearwardly of the arm so as to be in position for the next throwing operation.

If it is desired to operate the trap manually,

the operator may pull the trigger down to the solid line position shown in Figure 9, which will release the arm and throw the pigeon out. The height of the trajectory may be adjusted by loosening the bolt 20 and tilting the upper bracket 16 counter-clockwise from the position shown in Figure 5, to raise the trajectory. By swinging the lower bracket member 16 to the right or left by means of the handle 14 the trajectory will be altered to the left or right, respectively. When the adjusting screw 27 is screwed outwardly to increase the tension, the small inner spring 32 will be fully depressed, even when the throwing arm is in the outward, or released, position, so that the adjacent convolutions of the small spring 15 32 rest upon each other. When the tension on the spring 30 is reduced by screwing the member 27 inwardly and the throwing arm is in the released position, the small, inner spring 32 expands to take up any slack which might otherwise be present. After the arm is released, it swings outwardly, throwing the pigeon, and, as the throwing arm reaches the forward position, as shown in Figure 1, the cam 58 operates the arm 56 which applies the brake 52 to the drum 38 and arrests the arm, thereby preventing oscillation of the arm and preventing the arm from forcibly swinging past forward dead center. If this arm is permitted to oscillate it creates a considerable amount of vibration, and, if the operator should inadvertently be struck by this arm as it swings around, it is capable of causing severe injury. The brake completely arrests the arm as it passes forward dead center and thereby prevents such oscillation and reduces the possibility of injury to the operator. As the cam 58 moves the arm 56 outwardly to apply the brake, it simultaneously moves the rod 59 outward, thereby swinging the trigger operating arm 60 to the solid line position, as shown in Figure 1, permitting the spring 92 (see Figure 10) to restore the trigger 61 to the normal, or solid line, position of Figure 9.

If it is desired to release the trap by electrically energized means, a pair of conductor wires 97 and 98 are mounted to binding posts 99 and 100, respectively, which conductors are in turn connected to the coil of the electro magnet 73, enclosed in the housing 74 (see Figure 1) in a well known manner. Frequently, it is desirable to release the trap electrically by an official on the firing line, and this may be accomplished by connecting the conductors 97 and 98 through a battery, or other suitable source of electrical energy, not shown, and through an ordinary type of push button or key, also not shown. Such electrical operation is particularly desirable when throwing doubles from two different traps, as in skeet. Both traps can be connected through the same key, in a well known manner, so that by simultaneously forming a contact through both of the traps, the traps will both be released at the same instant.

It will be noted in Figures 10 and 11 that the throwing arm engages the pigeon on a shoulder 65 101 set inwardly from the outer flange of the pigeon. This is the standard type of clay pigeon and by thus engaging the pigeon on the inset shoulder, breakage of pigeons in throwing is greatly reduced, since this shoulder is a much 70 stronger portion of the pigeon than the outer flange.

The device comprises a simple, effective, and durable trap having all of the features desired by trap shooters, including rapid spinning 75

motion of the pigeon in flight, simplicity and ease of operation, since it is merely necessary to lay the pigeon on the table 18 and set the operating handle C, and rapidity of action, since two pigeons can be laid on the table 18 at the same time, as illustrated in Figure 6, and the second one used immediately after the first, as soon as the throwing arm can be again swung to a set position. The device is capable of extreme limits of adjustment, as shown in Figure 6, it being possible with the present trap to throw a pigeon directly vertically from the trap, if desired, and at any lateral angle through a radius of three hundred and sixty degrees.

15 I claim:

- 16 1. A target trap having a supporting base, a table adjustably mounted thereon, a throwing arm mounted to pivot in a plane parallel to the table top to engage a clay pigeon supported thereon, a drum rigidly connected to said throwing arm to rotate therewith, a cam carried by said drum, a brake operatively associated with said drum, cam actuated means connected to said brake to move said brake into engagement with said drum upon completion of an operative movement of said throwing arm.
- 20 2. A target trap having a supporting base, a throwing arm rotatably mounted thereon, a drum fixedly connected to said throwing arm, spring means mounted to forcibly rotate said arm to throw a pigeon, brake means operatively associated with said drum, and cam means carried by said drum and operatively connected to said brake means to move said brake means into braking engagement with said drum upon completion of an operating movement of said throwing arm.
- 25 3. A target trap having a supporting base, a table member supported thereby, a throwing arm

adapted to swing in a plane parallel to said table to engage a clay pigeon supported on said table, actuating means operatively engaging said throwing arm to forcibly rotate said arm with respect to said table to throw a pigeon supported on said table, trigger means adapted to releasably retain said throwing arm against the force of said actuating means, an arm pivotally mounted to normally engage an element of said trigger means, and electrically controlled means mounted to hold said arm out of engagement with said trigger element, and to release said arm upon energization of said electrically controlled means to engage and actuate said trigger to release said throwing arm.

15 4. A target trap having a supporting base, a table member supported thereby, a throwing arm adapted to swing in a plane parallel to said table to engage a clay pigeon supported on said table, actuating means operatively engaging said throwing arm to forcibly rotate said arm with respect to said table to throw a pigeon supported on said table, trigger means adapted to releasably retain said throwing arm against the force of said actuating means, an arm pivotally mounted to normally engage an element of said trigger means, electrically controlled means mounted to hold said arm out of engagement with said trigger element, and to release said arm upon energization of said electrically controlled means to actuate said trigger to release said throwing arm, a cam carried by said throwing arm to rotate therewith, and cam actuating means connected to said trigger operating arm to move said arm to engagement with said electrically controlled means upon completion of a throwing operation of said throwing arm.

ARTHUR E. ROTH.
